UNITED STATES PATENT OFFICE

ARNOLD J. DECKER, OF WYANDOTTE, MICHIGAN, ASSIGNOR TO ALL METAL PRODUCTS COMPANY, OF WYANDOTTE, MICHIGAN, A CORPORATION OF DELAWARE

DESIGN FOR A TOY ROADSTER

Application filed December 26, 1931. Serial No. 42,212. Term of patent 3½ years.

To all whom it may concern:

Be it known that I, ARNOLD J. DECKER, a citizen of the United States, residing at Wyandotte, in the county of Wayne and State of Michigan, have invented a new, original, and ornamental Design for Toy Roadster, of which the following is a specification, reference being had to the accompanying drawings, forming part thereof.

Fig. 1 is a side elevation of a toy roadster showing my new design.

Fig. 2 is a plan view thereof.

Fig. 3 is a bottom view of the toy roadster.

Fig. 4 is a front elevation thereof.

I claim:

The ornamental design for a toy roadster, as shown.

ARNOLD J. DECKER.
